(57) **CLAIM**

The ornamental design for a medicament pocket, as shown and described.

DESCRIPTION

FIG. 1 is a perspective view of a first embodiment of a medicament pocket of the present design;

FIG. 2 is a front view of the first embodiment thereof;

FIG. 3 is a rear view of the first embodiment thereof;

FIG. 4 is a left side view of the first embodiment thereof;

FIG. 5 is a right side view of the first embodiment thereof;

FIG. 6 is top view of the first embodiment thereof;

FIG. 7 is bottom view of the first embodiment thereof;

FIG. 8 is a cross-sectional view, taken at line 8-8 of FIG. 2 of the first embodiment thereof;

FIG. 9 is a cross-sectional view, taken at line 9-9 of FIG. 1 of the first embodiment thereof;

FIG. 10 is a perspective view of a second embodiment of a medicament pocket of the present design;

FIG. 11 is a front view of the second embodiment thereof;

FIG. 12 is a rear view of the second embodiment thereof;

FIG. 13 is a left side view of the second embodiment thereof;

FIG. 14 is a right side view of the second embodiment thereof;

FIG. 15 is top view of the second embodiment thereof;

FIG. 16 is bottom view of the second embodiment thereof; and

FIG. 17 is a cross-sectional view, taken at line 17-17 of FIG. 11 of the second embodiment thereof; and,

FIG. 18 is a cross-sectional view, taken at line 18-18 of FIG. 10 of the second embodiment thereof.

The portions of the drawings shown in broken lines represent environmental structure and form no part of the claimed design.
